UNITED STATES PATENT OFFICE.

ERNEST L. SONS, OF PITTSBURGH, PENNSYLVANIA, ASSIGNOR OF ONE-HALF TO
SAMUEL A. BOYD AND ONE-FOURTH TO WILLIAM L. McCANDLESS, BOTH OF
PITTSBURGH, PENNSYLVANIA.

MARINE VESSEL.

1,224,678.

Specification of Letters Patent.

Patented May 1, 1917.

Application filed June 21, 1916. Serial No. 104,867.

To all whom it may concern:

Be it known that I, ERNEST L. SONS, a citizen of the United States, residing at Pittsburgh, county of Allegheny, and State 5 of Pennsylvania, have invented certain new and useful Improvements in Marine Vessels, of which the following is a specification.

This invention relates to marine vessels, more particularly to the providing of the 10 hull or frame of the vessel with means to prevent the sinking thereof, and has for its object to provide a vessel, in a manner as hereinafter set forth, with sustaining elements, consisting of independent air containing receptacles, disposed throughout the 15 frame and floors of the decks to arrest the submerging or sinking of the vessel when the hull of the latter is damaged or stove in.

Further objects of the invention are to 20 provide a marine vessel with sustaining elements simple in construction and arrangement, strong, durable, efficient in use, conveniently positioned or arranged with respect to the hull and floors of the decks and 25 comparatively inexpensive when used.

With the foregoing and other objects in view the invention consists of the novel construction, combination and arrangement of 30 parts, as hereinafter more specifically described and illustrated in the accompanying drawing, wherein is shown an embodiment of the invention, but it is to be understood that changes, variations and modifications 35 can be resorted to which come within the scope of the claims hereunto appended.

In the drawing wherein like reference characters denote corresponding parts throughout the several views:

Figure 1 is an elevation, broken away, of 40 a vessel showing the adaptation thereto of sustaining elements in accordance with this invention.

Fig. 2 is a perspective view of a sustaining 45 element.

Fig. 3 is a cross sectional view thereof.

Referring to the drawings in detail 1 50 notes the keel and 2 the bow of a vessel. The bow 2, sides and stern (latter not shown) of the hull of the vessel are formed from an inner and outer frame. This is clearly shown with respect to the sides and outer frame and is indicated at 3 and the inner frame at 4. As illustrated the vessel is shown as provided with four lower decks

5, 6, 7 and 8 and the floor of each of said 55 decks consists of an upper section 9, and a lower section 10 and the said sections 9, 10, are spaced from each other. The lower sections 10 of the floors of the decks 5, 6, and 7 provide the top of the decks 6, 7 and 8. 60

The decks are divided by one or more vertical partitions, only one being shown, and which consists of spaced sections, 11 and 12. The partitions also provide means for bracing the decks and when one is employed, 65 which is arranged centrally of the hull, it extends to and is supported by the keel 1, as well as depending below the section 10 of the floor of the lowermost deck 8.

The sustaining elements which are used 70 to prevent submerging or sinking of the hull are arranged between the frames forming the hull, between the sections of the floors of the decks and between the sections of the partition or partitions.

The sustaining elements are referred to generally by the reference character 13 and are arranged in longitudinal extending rows between the frames of the hull, the sections of the deck floors and the sections of the 75 partition or partitions. The rows of sustaining elements positioned between the frames of the hull extend from the keel 1 to the top of the hull, the rows of sustaining elements arranged between the sections 80 of the deck extend from the bow to the stern of the vessel and the rows of sustaining elements positioned between the sections of the partition or partitions extend from the bow to the stern of the vessel. 90

The sustaining elements which are positioned between the frames of the hull are arranged at an angle with respect to the sustaining elements arranged between the floors 95 of the decks and the sustaining elements positioned between the sections of the partition or partitions are disposed at right angles with respect to the sustaining elements arranged between the sections of the floors of the deck.

Relative to this arrangement the sustaining elements positioned between the floors of the deck are mounted in a flat position, while those arranged between the sections of the partition or partitions are mounted on 100 edge. Relative to the sustaining elements between the frames of the ship certain of them are mounted on edge while others 105

conform to the curvature of said frames but even when conforming to such curvature are disposed at an angle with respect to the sustaining elements arranged between the sections of the floors of the decks.

Each of the sustaining elements consists of an oval-shaped closed metallic casing 14 embodying a pair of side walls 15, 16, a bottom wall 17, a top wall 18 and a pair of end walls 19. The top wall 18 of each of the casings has a longitudinal extending and centrally disposed depressed portion 20 provided with an inlet check-valve 21 which opens into the chamber 22 formed by the 15 casing.

Associated with each row of sustaining elements is an air supply pipe 24, disposed longitudinally, and communicating with the check valves 21 of the sustaining elements 20 forming the row. The supply pipe 24 is either connected to a feed pipe (not shown) and which communicates with an air-compressor (not shown) or a compressor can be attached to a pipe 24.

25 The casings 14 of a row, are independent of each other, and are adapted to be filled with air, from any suitable source of air supply, preferably by means of an air-compressor, or compressors, and the inlet check-valves 21 are of a known type so they will prevent the discharge of air but will allow the supply to a casing when desired.

30 By providing the rows of independent sustaining elements one may become damaged and which would not interfere with the other row.

What I claim is:—

35 1. A marine vessel comprising a hull including an inner and outer frame and fur-

ther having a deck floor formed of an upper 40 and lower section, a series of independent rows of air containing casings interposed between said frames, a series of independent rows of air containing casings interposed between said floor sections, each of said 45 casings having one wall depressed to provide a longitudinally extending groove, an inlet valvular device mounted in the bottom of each of said grooves, and a series of independent air supply pipes, each of said 50 pipes common to a row of casings, positioned in the grooves of and connected to the valvular device of the casings of the row.

2. A marine vessel comprising a hull including an inner and outer frame and further having a deck floor formed of an upper and lower section, a series of independent rows of air containing casings interposed between said frames, and a series of independent rows of air containing casings interposed between said floor sections, each of said 60 casings being oblong in plan and oval in cross section and each having one wall depressed to provide a longitudinal groove, an inlet 65 valvular device in the bottom of each groove, and a series of independent air supply pipes, each of said pipes common to a row of casings, positioned in the grooves of and connected to the valvular device of the casings 70 of the row.

In testimony whereof I affix my signature in the presence of two witnesses.

ERNEST L. SONS.
